(57) **CLAIM**

The ornamental design for a golf club stand, as shown and described.

DESCRIPTION

FIG. 1 shows a perspective view of a golf club stand; FIG. 2 shows a front view of the golf club stand; FIG. 3 shows a rear view of the golf club stand; FIG. 4 shows a right side view of the golf club stand; FIG. 5 shows a left side view of the golf club stand; FIG. 6 shows a top plan view of the golf club stand; and, FIG. 7 shows a bottom plan view of the golf club stand. The shade lines in the Figures show contour and not surface ornamentation.

Portions of the claimed design are shown separated and bound by a bracket to indicate indeterminate length.

1 Claim, 5 Drawing Sheets
